UNITED STATES PATENT OFFICE.

ARTHUR TREVOR DAWSON, OF WESTMINSTER, LONDON, AND JAMES HORNE, OF BARROW-IN-FURNESS, ENGLAND, ASSIGNEES TO VICKERS LIMITED, OF WESTMINSTER, ENGLAND.

AMMUNITION-LOADING APPARATUS.

1,182,989.

Specification of Letters Patent. Patented May 16, 1916.

Original application filed November 5, 1912, Serial No. 729,564. Divided and this application filed December 2, 1913. Serial No. 804,163.

To all whom it may concern:

Be it known that we, ARTHUR TREVOR DAWSON, knight, and JAMES HORNE, both subjects of the King of Great Britain, residing, respectively, at Vickers House, Broadway, Westminster, in the county of London, England, and Naval Construction Works, Barrow-in-Furness, in the county of Lancaster, England, have invented certain new and useful Improvements in Ammunition-Loading Apparatus, of which the following is a specification.

This invention relates to ammunition hoisting and loading apparatus of the kind in which the powder charges and the projectile are raised in a lower cage to a working chamber wherein the said powder charges and projectile are transferred from the lower cage to an upper or gun loading cage by which they are carried to the breech of the gun.

According to this invention the powder charge holder of the gun loading cage is adapted to be automatically moved to and from its loading position by means under the control of the rammer in such manner that as the rammer reaches its withdrawn position after each forward stroke the holder is angularly displaced to the required extent.

In order that the said invention may be clearly understood and readily carried into effect, we will describe the same more fully with reference to the accompanying drawings in which:—

Figures 1 and 2 are a side elevation and an end elevation of the gun loading cage showing means for automatically moving the powder charge holder. Figs. 3 and 4 are respectively an end elevation and a sectional plan showing more clearly the mechanism for automatically moving the powder charge holder, and Fig. 5 is a side elevation of a part of this mechanism.

The gun loading cage B comprises the rotary powder charge holder B' and the projectile tray B², the latter being, in the examples shown, pivoted to the cage by a transverse pivot b² to enable the tray to as-

sume an inclined position during the ascent and descent of the cage as is well understood. 50 The powder charge holder B' is provided with two separate compartments b b' and is adapted to be rocked about a pivot B'x in order to bring its compartments successively opposite the breech chamber of the gun for 55 loading, the said pivot being equidistant from the axes of the compartments b, b' and the axis of the gun.

The means for automatically moving the holder B' comprise a hydraulic cylinder B⁴ fixed to the loading arm, the ram of which is connected to a rack member b⁴ that engages with a pinion b^{4x} connected to or integral with a tappet lever B^{4x}. The cage B has a bracket B⁵ which carries a disk b⁵ provided with a projecting stud b^{5x} which bears against the shoulder of the tappet lever as shown. The said disk is connected through a shaft b⁶, and a pinion b^{6x} to a second pinion B⁶ on the pivot B'x of the holder B'. 70 The hydraulic cylinder B⁴ is under the control of a valve B⁸ (Fig. 1) which is arranged in such manner that as the cage reaches its loading position it is operated to place the right hand end of the cylinder to exhaust so 75 that the pressure fluid constantly acting on the left hand face of the ram tends to displace the latter to the right, but is prevented from doing so by the spring bolt B^{5x} which passes through a hole in the disk b⁵ and engages with a recess in the bracket B⁵. The said bolt is carried by the disk b⁵ as are also two other similar bolts b⁸, b⁹.

Arranged contiguous to the rammer head A⁰ (Fig. 3) is a lever B⁷ mounted on a 85 spring controlled shaft B^{7x} having an arm b⁷ adapted to coöperate with a bell crank lever b^{7x} appertaining to the spring bolt B^{5x}. When the rammer head moves forward to ram the shell the shaft B^{7x} is moved by 90 its spring so that the arm b⁷ assumes a position out of the path of the lower arm of the bell crank lever b^{7x} which is then moved to the left, (Fig. 3) by a light spring which bears on the upper arm of the lever b^{7x} 95 and is carried by the bolt B^{5x}. On the

rammer being withdrawn, the head A⁰ coöperates with the lever B⁷ to cause the arm b⁷ to engage with the right side of the lower arm of the lever b^{7x} and thereby withdraw the spring bolt B^{5x} clear of its recess in the bracket B⁵. The ram and the rack member b⁴ attached thereto can now move and in so doing displaces the holder B' about its pivot B'^x through the aforesaid gearing until the first half powder charge is in line for ramming, whereupon the holder is locked by the engagement of the second spring bolt b⁸ with the aforesaid recess in the bracket B⁵, this bolt having moved with the disk into the position previously occupied by the bolt B^{5x}. During this movement, the ram has been displaced a certain distance toward the right. The first half charge is then rammed and when the rammer head returns, the said second bolt b⁸ is released by the engagement of the arm b⁷ with the bell crank lever b^{8x} in a similar manner to that described with reference to the bolt B^{5x}, whereupon the holder B' is displaced as before until its movement is stopped by the engagement of the third spring bolt b⁹ with the recess in the bracket B⁵ when the second half powder charge is in line for ramming. During this movement, the ram has been displaced toward the right a further distance equal to that mentioned in connection with the first displacement of the holder B'. The latter half charge is then rammed and on the rammer head returning, the bolt b⁹ is released as described with reference to the bolts B^{5x} and b⁸. The powder holder is again angularly displaced until it resumes its normal position (after having completed one revolution) and is then locked by the spring bolt B^{5x}, the ram moving a further equal distance to the right. When the cage is being lowered the disk b⁵ moves clear of the tappet lever B^{4x} on the loading arm, the aforesaid control valve is operated in the direction to admit pressure fluid to the right hand end of the cylinder B⁴ and the ram and the parts operated thereby are thus restored to their original position as shown in Figs. 2 and 4, the ram thus returning to the position shown in Fig. 3 in being displaced to the left a distance equal to the sum of the distances through which it was moved on the return strokes of the rammer.

In the example illustrated a portion B^{2xx} of the projectile tray B² of the gun loading cage, namely the part adjacent to the powder holder B, is hinged longitudinally by the spindle b^{2xx} to the fixed part so as to be capable of being lowered automatically when the powder holder B' is being moved about its pivot B'^x to bring the powder charges into the ramming positions.

What we claim and desire to secure by Letters Patent of the United States is:—

1. In ammunition hoisting and loading apparatus for heavy ordnance, the combination with the projectile tray of the gun loading cage, of a powder charge holder having separate powder charge compartments, means for rotatably mounting said holder relatively to the said tray, and means brought into operation by the return movements of the rammer for automatically displacing said holder. 75

2. In ammunition hoisting and loading apparatus for heavy ordnance, the combination with the gun loading cage, of a powder charge holder having separate powder charge compartments, means for rotatably mounting said holder, a hydraulic press connected to said holder, a control valve for said press, and a device on the gun loading cage for coöperating with said valve. 80

3. In ammunition hoisting and loading apparatus for heavy ordnance, the combination with the projectile tray of the gun loading cage, of a powder charge holder having separate powder charge compartments, means for rotatably mounting said holder relatively to said tray, a hydraulic press connected to said holder, a control valve for said press, a device on the gun loading cage for coöperating with the valve to cause it to admit pressure fluid to said press, and means operated by the rammer for normally preventing said press from moving the holder. 90

4. In ammunition hoisting and loading apparatus for heavy ordnance, the combination with the projectile tray of the gun loading cage, of a powder charge holder having separate powder charge compartments, means for rotatably mounting said holder relatively to said tray, a hydraulic press connected to said holder, a control valve for said press, a device on the gun loading cage for coöperating with the valve to cause it to admit pressure fluid to said press, and means operated by the rammer for normally preventing said press from moving the holder, and when so operated for allowing the press to move the holder only to a predetermined extent. 100

5. In ammunition hoisting and loading apparatus for heavy ordnance, the combination with the projectile tray of the gun loading cage, of a powder charge holder having separate powder charge compartments, means for rotatably mounting said holder relatively to said tray, a hydraulic press connected to said holder, a member moved by said press, a member connected to said holder, a spring bolt device for normally connecting the two members together, and means under the control of the rammer for moving said spring bolt device into the disconnected position. 115

6. In ammunition hoisting and loading apparatus for heavy ordnance, the combina- 130

tion with the projectile tray of the gun loading cage, of a powder charge holder having separate powder charge compartments, means for rotatably mounting said 5 holder relatively to said tray, a hydraulic press connected to said holder, a member moved by said press, a member connected to said holder, three spring bolt devices each of which in turn serves to connect the two 10 members together, and means under the control of the rammer for moving each of the said spring bolt devices in turn into its disconnected position.

In testimony whereof we affix our signatures in presence of two witnesses.
